Attorney, Agent, or Firm—Bruce E. Burdick

[57] **CLAIM**

The ornamental design for a packaging container for ammunition, substantially as shown and described.

DESCRIPTION

FIG. 1 is a top, front perspective view of the packaging container for ammunition showing our new design; and FIG. 2 is a bottom, rear perspective view thereof. The end not seen is the same in appearance as the end shown.

FIG. 1

FIG. 2
